UNITED STATES PATENT OFFICE

GEORGE J. MEUER AND WILLIAM C. STEVENS, OF MILWAUKEE, WISCONSIN, ASSIGNEES,
BY MEANS ASSIGNMENTS, TO CUTLER-HAMMER, INC., A CORPORATION OF DELA-
WARE

RESISTANCE CONTROL DEVICE

Application filed October 5, 1935. Serial No. 60,391.

This invention relates to improvements in resistance control devices of the type employed in radio and similar apparatus.

An object of the invention is to provide a resistance control device of simple and durable construction.

Another object is to facilitate assembly of the several elements of the device.

Another object is to provide interchangeable elements whereby the electrical characteristics of the device may be altered as desired.

Another object is to provide novel means for removably securing the device to a panel or other support.

Another object is to provide improved supporting and securing means for the resistance elements of devices of this character.

Other objects and advantages of the invention will hereinafter appear.

In the accompanying drawing, wherein are illustrated certain of the embodiments which the invention may assume in practice,

Figure 1 is a vertical sectional view of a radio rheostat constructed in accordance with my invention;

Fig. 2 is a rear elevational view of the device shown in Fig. 1;

Fig. 3 is a vertical sectional view of a modified form of the device illustrated in Fig. 1, whereby the same is adapted for use as a potentiometer;

Fig. 4 is a rear elevational view of the device shown in Fig. 3; and,

Fig. 5 is a sectional view on the line 5—5 of Fig. 3.

Referring to Figs. 1 and 2 of the drawing, the numeral 10 designates a metallic hub member having a reduced end portion 11 of a size corresponding to the size of opening 12 in a metallic member 13. The member 13 abuts a shoulder 14 on hub member 10, and the end portion 11 of the latter is adapted to be spun or riveted over the member 13, as indicated at 15, to secure said parts against relative movement. Hub member 10 is internally screw-threaded, as indicated at 16, to receive an externally screw-threaded cooperative clamping member 17. The members 10 and 17 are adapted to be brought together

from opposite sides of a perforated insulating panel 18, or other suitable support, into clamping engagement with the latter, the member 17 being provided with a polygonal head 19 for engagement by a wrench or the like. The member 17 is also preferably provided with a tapered portion 20 to assist in centering the same within the perforation, and also to insure a proper clamping action of said members.

Rotatably mounted upon the hub member 10 is a substantially cylindrical insulating base member 21, the latter having an annular projecting portion 22 (Figs. 1 and 5), which is provided with a groove 23. Groove 23 is concentrically disposed within the annular projecting portion 22, whereas the continuity of the former is interrupted as indicated at 24 to provide abutments 25 and 26 for engagement with a stationary projection 27 upon the member 13. Rotary movement of base member 21 is thus limited for a purpose hereinafter set forth.

The base member 21 is also provided with a peripheral cut-away portion 28 to receive the resistance element 29, the annular shoulder 30 being adapted to definitely position said element with respect to the base. As shown, said resistance element comprises a flexible strip of insulating material 31 around which a suitable number of turns of relatively fine wire 32 are wound in closely adjacent relationship to each other. Each end of the wire 32 is preferably threaded one or more times through suitable openings 33 and 34 near the respective ends of the strip to prevent slippage or unwinding of the wire, whereas one end thereof leads off from the wound portion as indicated in dotted lines at 35 (Fig. 2).

The rear face of base member 21 is provided with a notch or recess 36 to receive a substantially U-shaped metallic member 37 the reduced end portions 38 and 39 of the latter being adapted to pass through corresponding openings in the ends of flexible strip 31, whereas said ends 38 and 39 are thereafter bent, as shown in Fig. 2, to hold the ends of said strip in the desired position. In practice the arms of the U-shaped member 100

37 are preferably brought sufficiently close together to provide a slightly reduced circumference of the completed resistance element whereby the latter is required to be sprung over the cut-away portion 28 of the base member, thus frictionally holding said element in position, while positively preventing relative rotary movement of said element and said base member.

10 The rear face of base member 21 is also provided with a plurality of radially arranged segmental or triangular ridges or projections 40, said projections being spaced apart as shown to provide a corresponding number of 15 radial slots or channels 41. Said slots are adapted to receive the radial spring fingers 42 of a disk-shaped member 43. Member 43 is provided with a central opening 44 and a pair of tongues or projections 45 adapted to 20 take within a corresponding slot 46 in the reduced end 47 of a tubular member 48. Wire 35 is adapted to be laid in slot 46, and the same is clamped therein by said tongues 45, the reduced end 47 being thereafter riveted 25 or bent over the member 43, as indicated at 49, to hold said parts together, with the spring fingers 42 compressed. The member 43 therefore tends to draw the member 48 backwardly, but such movement is limited by 30 engagement of a shoulder 50 on the latter with the annular internal flange 51 on hub member 10. Moreover, this arrangement insures positive electrical engagement between member 48 and hub member 10. Member 48 35 is freely rotatable within the member 17, whereas the former is provided with a screw-threaded portion 52 for engagement by a correspondingly threaded insert 53 in a molded knob or handle 54. A pointer or indicator 40 55 is also preferably threaded onto portion 52 prior to the knob 54, whereby said pointer and knob may act as lock nuts with respect to each other to bind or lock the same to member 48. It will thus be seen that rotary movement of knob 54 in one direction or the other 45 will effect corresponding movement of the resistance element 29, due to the interlocking connections aforescribed.

50 The member 13 is provided with an enlarged rearwardly bent portion 56 of arc-shape, said member being perforated as indicated at 57 to facilitate such bending thereof. The arc-shaped portion 56 is provided with a plurality of perforations 58, 59 and 60, 55 whereas each of said openings is provided with an insulating lining by means of the annular in-bent flanges 61 on an insulating strip 62, as clearly shown in Fig. 1. A screw 63 passes upwardly through insulated opening 60, and a washer 64 of brass or other conducting material is placed thereover. A nut 65 is threaded onto said screw to hold the same in position. As will be apparent the screw 63 is in electrically conductive relation to portion 56 of member 13. Screw 63 is therefore

adapted to serve as one of the circuit terminals, a nut 66 being provided for clamping the circuit wire thereto.

5 A screw 67 passes through the insulated opening 58 at the opposite end of portion 56, said screw being in electrical contact with and adapted to support an elongated contact member 68. An insulating washer 69 is placed over the upper end of screw 67 and the several parts are held in position by the nut 70. It will thus be seen that screw 67 is completely insulated from portion 56 of member 13. A nut 71 is adapted to provide for connection of the other wire of the circuit. The intermediate opening 59 in portion 56 is not utilized in the arrangement illustrated in Figs. 1 and 2,—the same being adapted to facilitate the circuit connections illustrated in Figs. 3, 4 and 5 as hereinafter described.

75 Contact member 68 is preferably provided with a relatively narrow inward projection or rib 72 for engagement with the coils of resistance wire 32. The flexible strip 31 is also preferably provided with a boss or projection 73 for engagement with rib 72, as shown, to insure disengagement of the latter from wire 32 when the parts are in the position illustrated in Fig. 2. In said position circuit is interrupted, whereas upon turning of knob 54 in a clockwise direction circuit is completed, to first include all of the resistance and then gradually exclude the same upon continued clockwise movement of said knob. Such clockwise movement of the knob and its associated elements is limited by engagement of the shoulder 25 with projection 27 (shown in dotted lines in Fig. 2), at which time a minimum amount of resistance is included in circuit.

80 Assuming attachment of the circuit wires 105 to screws 67 and 63 by means of nuts 71 and 66, respectively, and further assuming movement of knob 54 so that contact member 68 engages the resistance wire 32, continuity of circuit may be traced from screw 67 through contact member 68, through the resistance wire 32 from the point of contact of said member 68 to the end 35 of said wire, thence through tubular member 48 to hub member 10, to member 13 and portion 56, through metallic washer 64 and nut 65 to screw 63, and thence to the circuit wire connected to the latter.

110 The device illustrated in Figs. 3, 4 and 5 is in many respects identical with that shown in Figs. 1 and 2, certain changes and additions being incorporated, however, to adapt the same for use as a potentiometer. Thus, the resistance element 29^a preferably comprises a relatively wider flexible insulating strip 31^a 115 upon which is wound a wire 32^a which is finer than that employed in the device of Figs. 1 and 2. Moreover said wire is wound more closely adjacent to the ends of the flexible strip 31^a so that the member 68 is in electrical 120

125 130

engagement with the resistance element in each extreme position of the latter.

Surrounding the annular projection 22 of base member 21 is a metallic ring 74, said ring having a nib or projection 75 around which one end of the resistance wire 32^a is wound and fastened by soldering, as indicated at 76 (Fig. 5). The other end 35 of said wire is connected as described in connection with Figs. 1 and 2. A screw 77 passes through the intermediate insulated opening 59 in portion 56, said screw being in electrical engagement with and adapted to support a yoke-shaped contact element or brush 78, the curved arms 79 and 80 of the latter being in alignment with contact ring 74 and provided with small bosses or projections 81 and 82 which are held in engagement with said ring. An insulating washer 83 provides for complete insulation of screw 77 from portion 56, whereas a nut 84 is adapted to hold the screw and its associated parts in position. A nut 85 provides for connection of a circuit wire in electrical engagement with the screw 77. The device illustrated in Figs. 3 to 5 is otherwise exactly like that shown in Figs. 1 and 2, and further description thereof is deemed unnecessary.

With each of screws 63, 77 and 67 suitably connected in circuit by means of the nuts 66, 85 and 71, respectively, continuity of circuit may be traced from the screw 67 through contact 68 to a given point in the resistance element, thence in one direction to the lead wire 35, through member 48, hub 10, member 13 and portion 56 to screw 63, as set forth in connection with Figs. 1 and 2. An additional circuit is herein provided, which may be traced from said contact 68 through the remainder of the resistance wire to the ring 74, thence through the brush or contactor 78 to screw 77. By the arrangement aforescribed the well known potentiometer circuit connections may be effected.

The manner of assembling the respective devices will be apparent from the foregoing description. It may be further noted, however, that after spinning over or riveting the reduced end 47 of member 48, as indicated at 49 in Fig. 3, the mechanical and electrical contact of the several parts is enhanced or insured by soldering, as indicated in dotted lines at 86 in said figure, this feature being omitted from the other figures for clarity of illustration.

In practice different sized wires 32 are employed for providing resistance elements of different ohmic values, whereas the ohmic value of a particular resistance element is preferably marked upon an uncovered portion of the flexible insulating strip 31 after winding of the resistance wire. When coated wire is employed for the resistance elements such coating is preferably removed from the upper surface of such elements to insure good electrical contact with the member 68.

What I claim and desire to secure by Letters Patent is:

1. In resistance control apparatus, the combination with a metallic hub member, of a metallic terminal supporting member rigidly secured thereto, a headed member adapted for screw-threaded engagement with said hub member for attachment of the latter to an insulating panel or other support, a substantially cylindrical insulating block rotatably mounted on said hub member, an operating shaft axially penetrating said headed member, means at one end of said shaft for effecting rotation thereof, and means at the other end of said shaft for positively engaging said insulating block.

2. In resistance control apparatus, the combination with a metallic hub member, of a metallic terminal supporting member rigidly secured thereto, a headed member adapted for screw-threaded engagement with said hub member for attachment of the latter to an insulating panel or other support, a substantially cylindrical insulating block rotatably mounted on said hub member, an operating shaft axially penetrating said headed member, means at one end of said shaft for effecting rotation thereof, means at the other end of said shaft for positively engaging said insulating block, and a resistance element frictionally secured to said block for rotation therewith.

3. In resistance control apparatus, the combination with a metallic hub member, of a metallic terminal supporting member rigidly secured thereto, a headed member adapted for screw-threaded engagement with said hub member for attachment of the latter to an insulating panel or other support, a substantially cylindrical insulating block rotatably mounted on said hub member, an operating shaft axially penetrating said headed member, means at one end of said shaft for effecting rotation thereof, means at the other end of said shaft for positively engaging said insulating block, a resistance element frictionally secured to said block for rotation therewith, one end of said resistance element being electrically connected with said terminal supporting member through said shaft and said hub member, and a contactor supported by but insulated from said terminal supporting member, said contactor being adapted for sliding engagement with said element.

4. In resistance control apparatus, the combination with a metallic hub member, of a metallic terminal supporting member rigidly secured thereto, a headed member adapted for screw-threaded engagement with said hub member for attachment of the latter to an insulating panel or other support, a substantially cylindrical insulating block rotatably mounted on said hub member, an operating shaft axially penetrating said headed mem-

ber, means at one end of said shaft for effecting rotation thereof, means at the other end of said shaft for positively engaging said insulating block, a resistance element frictionally secured to said block for rotation therewith, one end of said resistance element being electrically connected with said terminal supporting member through said shaft and said hub member, a metallic ring electrically connected with the other end of said element, and a contact element carried by but insulated from said terminal supporting member for engagement with said ring.

5. In resistance control apparatus, the combination with a metallic hub member, of a metallic terminal supporting member rigidly secured thereto, a headed member adapted for screw-threaded-engagement with said hub member for attachment of the latter to an insulating panel or other support, a substantially cylindrical insulating block rotatably mounted on said hub member, an operating shaft axially penetrating said headed member, means at one end of said shaft for effecting rotation thereof, means at the other end of said shaft for positively engaging said insulating block, a resistance element secured to said block for rotation therewith, one end of said resistance element being electrically connected with said terminal supporting member through said shaft and said hub member, a metallic ring electrically connected with the other end of said element, a contact element adapted for engagement with said ring, and a contactor adapted for engagement with said resistance element, said contact element and contactor being respectively supported by but insulated from said terminal supporting member.

40. In resistance control apparatus, the combination with a metallic hub member, of a metallic terminal supporting member of substantially L-shape in cross-section rigidly secured thereto, a plurality of binding posts carried by said supporting member, certain of said binding posts being insulated therefrom, contactors carried by said last mentioned binding posts, an insulating block rotatably mounted on said hub member, a contact ring carried by said block and adapted for engagement with one of said contactors, a resistance element peripherally mounted on said block for rotation therewith and adapted for engagement with the other of said contactors, said element comprising a flexible insulating strip having wire wound thereabout, a metallic link for biasing the ends of said strip toward each other, means for electrically connecting one end of said wire and said ring, and means for effecting continuity of circuit between the other end of said wire and said terminal supporting means, said means comprising an operating shaft in contact with said wire and said hub member.

7. In resistance control apparatus, the combination with a metallic hub member, of a metallic terminal supporting member of substantially L-shape in cross-section rigidly secured thereto, a plurality of binding posts carried by said supporting member, certain of said binding posts being insulated therefrom, contactors carried by said last mentioned binding posts, an insulating block rotatably mounted on said hub member, a contact ring carried by said block and adapted for engagement with one of said contactors, a resistance element peripherally mounted on said block for rotation therewith and adapted for engagement with the other of said contactors, said element comprising a flexible insulating strip having wire wound thereabout, a metallic link for biasing the ends of said strip toward each other, means for electrically connecting one end of said wire and said ring, means for effecting continuity of circuit between the other end of said wire and said terminal supporting means, said means comprising an operating shaft in contact with said wire and said hub member, and a disk-shaped member riveted to said shaft, said member having a plurality of inwardly extending resilient projections adapted for engagement with co-operative abutments on said block for effecting rotation of the latter.

8. In a resistance control device, the combination with a fixed hub member, of an insulating block rotatably carried thereby, means carried by said hub member for limiting rotary movement of said block in each direction, a rotatable shaft extending through said hub member, and means on said shaft adapted to positively engage cooperating projections on the rear end of said block for effecting rotary movement of the latter.

9. In a resistance control device, the combination with a fixed hub member, of an insulating block rotatably carried thereby, a rotatable shaft extending through said hub member, and resilient means on said shaft having radial arms adapted for positive interlocking engagement with cooperating projections on said block for effecting rotary movement of the latter, said means being also adapted to effect positive electrical engagement between said shaft and said hub member.

10. In a resistance control device, the combination with a fixed hub member, of an insulating block rotatably carried thereby, means carried by said hub member for limiting rotary movement of said block in each direction, a rotatable shaft extending through said hub member, and means on said shaft adapted to positively engage said block for effecting rotary movement of the latter, said means comprising a disk-shaped member having a plurality of radial arms adapted to engage corresponding projections on said block.

11. In a resistance control device, the combination with a metallic hub member having a metallic terminal supporting member rigidly secured thereto, of means for rigidly securing said hub member to a panel or other support, an insulating block rotatably mounted on said hub member, means comprising a metallic shaft penetrating said hub member for effecting rotary movement of said block with respect to said hub member, means for limiting such movement of the block, a resistance element comprising a wire-wound flexible insulating strip, said element being circumferentially arranged on and frictionally secured to said block, one end of said resistance element being electrically connected to said shaft, and a contactor adapted to engage said element, said contactor being carried by but insulated from said terminal supporting member. 80 85
12. In a resistance control device, the combination with a metallic hub member having a metallic terminal supporting member rigidly secured thereto, of means for rigidly securing said hub member to a panel or other support, an insulating block rotatably mounted on said hub member, means comprising a metallic shaft penetrating said hub member for effecting rotary movement of said block with respect to said hub member, means for limiting such movement of the block, a resistance element comprising a wire-wound flexible insulating strip, said element being circumferentially arranged on and frictionally secured to said block, one end of said resistance element being electrically connected to said shaft, terminals carried by said terminal supporting member, one of said terminals being in electrical engagement therewith, another of said terminals being insulated therefrom, and a contactor carried by said last mentioned terminal, said contactor being adapted for engagement with said element. 90 95 100
13. In a resistance control device, the combination with a substantially cylindrical insulating block, of a resistance element comprising a strip of flexible insulating material having a wire wound thereabout, said element being bent around said block, and means comprising a self-sustaining inwardly bowed resilient metallic member having hooked ends penetrating corresponding openings in the ends of said strip to bias the latter toward each other solely by the resiliency of said member and thereby frictionally hold said element against movement axially of said block, said member being adapted to fit loosely within a notch in said block to prevent relative rotary movement of said element and said block. 110 115 120 125
14. A resistance element comprising a flexible strip of insulating material having a resistance wire wound thereabout, said strip being bent to form a circle of predetermined diameter, and means tending to maintain such diameter, said means comprising a self-sustaining substantially U-shaped resilient metallic member the arms of which are provided with hooked ends adapted to penetrate corresponding openings in the respective ends of said strip to bias the latter toward each other solely by the resiliency of said member. 70 75 80 85 90 95 100 105 110 115 120 125 130

In witness whereof, we have hereunto subscribed our names.

GEORGE J. MEUER.
WILLIAM C. STEVENS.
